UNITED STATES PATENT OFFICE.

JOSEPHINE BOWMAN, OF NEAR EIVINGTON, VIRGINIA.

WASHBOILER.

1,310,734.

Specification of Letters Patent. Patented July 22, 1919.

Application filed April 30, 1919. Serial No. 293,658.

To all whom it may concern:

Be it known that I, JOSEPHINE BOWMAN, a citizen of the United States, residing near Evington, in the county of Bedford and State of Virginia, have invented certain new and useful Improvements in Washboilers, of which the following is a specification.

This invention relates to devices for holding clothes in a submerged condition in a wash boiler during the boiling operation, and the object of the invention is to provide a device of this class which may be easily inserted in and withdrawn from the boiler and which may be quickly and securely locked in any desired position and as quickly unlocked and withdrawn.

In the accompanying drawings:—

Figure 1 is a top plan view of a wash boiler with the attachment in position for use, and showing by dotted lines the locking arms in locking position.

Fig. 2 shows a vertical central section of the boiler and attachment with the locking arms in retracted position and the actuating lever raised and in position to be used as a handle to lift the follower from the boiler.

Fig. 3 shows a vertical central section through the lower part of the boiler and attachment with the actuating lever depressed and the locking arms in their extended position.

Fig. 4 is a perspective view of the attachment, the upper part of the lever being cut away.

The follower comprises a bottom plate 1 provided with a plurality of openings to permit steam to pass through it and a peripheral upwardly extending flange 2 which is also preferably perforated. A lever 5 is pivotally connected at its inner end with the follower by a rod 4 which extends across the middle portion of the follower and is supported by the flange 2. Holes 6 and 7 are formed in the inner portion of the lever above and below the rod 4. These holes are disposed on opposite sides of the central longitudinal axis of the lever, as shown in Fig. 2. 8 and 9 indicate two locking arms disposed on opposite sides of the lever which are pivotally connected therewith, extend through the end walls of the follower and are adapted to engage the inner end walls of the boiler. The arm 8 on one side of the lever is pivoted therewith at 6, while the other arm 9 is pivotally connected with the lever at 7. Preferably each of said arms

is made of a single piece of stout wire and is oblong in form. The wires pass through the openings 6 and 7 and through openings in the end walls of the follower, the ends of the wires being bent toward each other to provide portions 10 which are adapted to engage the boiler.

When the lever 5 is in an upright position, as indicated in Fig. 2, the arms are out of contact with the boiler and the follower may be freely raised and lowered, and may be removed from the boiler. When the lever is in the upright position shown in Fig. 2, the extreme lower end of the lever below its pivotal connection with the follower, engages the bottom plate of the follower and by reason of this engagement and the arrangement of the arms, the lever is held in an upright position.

When the boiler is supplied with clothes to be boiled, the follower is lowered and pressed down upon the clothes by means of the actuating lever and then the lever is turned to a substantially horizontal position, in the manner indicated in Fig. 3, in such manner as to extend the arms and cause them to engage the side walls of the boiler. In this way the follower is pressed down upon the clothes and holds them in submerged condition and is prevented from rising during the boiling operation by reason of the engagement of the arms with the boiler. While the clothes are thus held submerged, steam can freely rise and the water can boil without interference but yet is prevented from rising to an unsafe extent.

It will be observed, by reference to Fig. 3, that when the lever is turned down to extend the arms the inner end of the arm 9 is above the pivotal connection of the lever with the follower while the inner end of the arm 8 is below it and the lever is wholly within the follower, its outer end being below its pivotal connection therewith. In this way a sufficiently long lever may be used which may project above the top of the boiler when being employed to raise and lower the follower, but which when the follower is locked to the boiler is so lowered that the top of the boiler may be applied without interference.

I claim as my invention:—

1. A wash boiler attachment, comprising a follower having a perforated horizontal bottom and upstanding sides, a lever pivot-

ally connected with the follower, and locking arms extending through the opposite end walls of the follower and pivotally connected with the lever on opposite sides of its 5 pivotal connection with the follower.

2. A wash boiler attachment, comprising a follower having a perforated horizontal bottom and a peripheral upstanding flange, a lever pivotally connected with the follower, and locking arms pivotally connected with the inner portion of the lever on opposite sides of its pivotal connection with the follower, each of which arms is made of stout wire which extends through an end 10 portion of the peripheral flange and is adapted to engage the boiler.

Copies of this patent may be obtained for five cents each, by addressing the "Commissioner of Patents, Washington, D. C."

3. A wash boiler attachment, comprising a follower having a perforated horizontal bottom and an upstanding peripheral flange, a lever having its inner portion 20 pivotally connected with the middle portion of the follower and adapted to engage at its extreme inner end the bottom of the follower, and locking arms pivotally connected with the inner portion of the lever 25 on opposite sides of its pivotal connection with the follower and which extend through the end walls of the follower and are adapted to engage the side walls of the boiler.

In testimony whereof I have hereunto 30 subscribed my name.

JOSEPHINE BOWMAN.
